CLAIM

The ornamental design for a shoe sole as shown and described.

DESCRIPTION

FIG. 1 is a rear, right and top perspective view of a shoe sole, showing my design.

FIG. 2 is a top, left and bottom perspective view thereof.

FIG. 3 is a top view thereof.

FIG. 4 is a bottom view thereof.

FIG. 5 is a front view thereof.

FIG. 6 is a rear view thereof.

FIG. 7 is a left view thereof; and,

FIG. 8 is a right view thereof.

The article shown is the design for a right foot shoe sole. The design also includes the article for the left foot which is not shown but is a mirror image of the article shown.

1 Claim, 8 Drawing Sheets
